UNITED STATES PATENT OFFICE

GISBERT RANKE, OF MASPETH, NEW YORK

MEANS FOR PROPELLING AND STEERING BOATS

Application filed January 27, 1932. Serial No. 589,127.

This invention relates to improvements in boat propelling devices as they are for instance disclosed in my copending application Serial No. 559,872, filed August 25th, 1931, and allowed November 30, 1931, of which this is a continuation in part.

It is the principal object of my invention to provide a simple and comparatively inexpensive device governing the propeller shafts 10 of boats and other water craft for lifting and lowering the propellers and for turning the same laterally at a desired angle to the boat.

Another object of my invention is the provision of twin propellers turning in opposite 15 directions on articulated inner and outer shafts, connected by a universal joint, and allowing a displacement of the propellers to vary the pitch to suit any prevailing conditions during the manoeuvring of the boat.

20 My invention will, therefore, allow a dispensation with oars or rudders, as the angular adjustment of the propellers laterally or horizontally as well as vertically will permit of imparting to the boat any desired turn.

25 A boat equipped with my improved articulated propeller shaft or shafts, if more than one shaft is used, has the point of union between operating and propeller shaft covered by a watertight sleeve, and can be manoeuvred 30 more readily than a boat with rigid propeller shafts.

Furthermore, when travelling in shallow waters or waters of unknown depths, the propellers can be lifted in order to clear the bottom, and even if the boat should touch bottom, the propellers could be elevated to clear the bottom and will still be operative to allow a floating of the boat, which will evidently be impossible with rigidly arranged propellers which will dig themselves into the ground.

35 Still another object of my invention is the provision of a boat propelling device including stub shafts carrying twin propellers 40 and articulated to the driving shafts which can be laterally displaced by the operator by means of a spindle connected with play to the stub shafts and having keys guided in grooves of a sleeve adapted to be rotated by means 45 of a cable guided over a pulley.

A further object of my invention is the provision of a screw bolt connected to the spindle in such manner so as not to hinder its movements, and operated by means of a bevel gear system from the operator's seat to raise 55 and lower said bolt and spindle and by the intermediary of its connections also the stub shafts carrying the propellers.

A still further object of my invention is the provision of a boat propelling device including 60 twin propellers so arranged upon the shafts as to mutually assist in their rotation by impinging the water used by one propeller blade against the corresponding propeller blade of the other propeller.

These and other objects and advantages of my invention will become more fully known as the description thereof proceeds and will then be specifically defined in the appended 65 claims.

70 In the accompanying drawing forming a material part of this disclosure:

Fig. 1 is a fragmentary sectional side elevation of the stern of a boat equipped with a propeller shaft governing device constructed 75 according to my invention.

Fig. 2 is a section on line 2—2 of Figure 1.

As illustrated, the stern part 10 of a boat, has a housing 11 erected over an opening 12 in the bottom of the boat through which extends a vertical spindle 13. To the lower forked end 14 of which is pivotally attached, as at 15, a member or link 16 having a slot 17 in its outer end in which is guided with play a pin 18 on a lip 19 of a bushing 20 in which are guided the inner and outer shafts 21, 22, for the propellers 23, 24, held thereon by lock nut 25. Shafts 21, 22, extend from the stern of the boat through brushing 26, and are made in two parts each of which carries one member of a universal joint in its housing 27 covered by a water-proof rubber mantle 28.

Spindle 13 is provided intermediate its ends with a plurality of keys 29 guided for vertical reciprocation in grooves on the inner face of a tubular housing or sleeve 30, rotatably held at its upper end in a bushing 31 at the inner part of a partition 32 in housing 11, and with its lower flanged end 33, in a ball bearing 34.

5 Spindle 13 enters housing 11 through a stuffing box 35 and a packing 36 provides a watertight closure. Near its lower end sleeve 30 carries a pulley 37 about which a cable 38 is guided over suitable rollers 39, 40, the ends of which are guided within convenient reach of the operator.

10 At its upper end above sleeve 30 spindle 13 carries a plate or head 41 rotatably held in a claw 42 gripping over table 41 and arranged at the lower end of a screw bolt 43 guided in a partition 44 of housing 11 into a bushing 45 at the upper end of housing 11 and guided therein by means of a collar 46.

15 A large bevel gear 47 stationary on a support 48 on partition 44 engages with its inner thread the thread of bolt 43, and runs on a ball bearing 49 at the lower end of bushing 45.

20 A small bevel gear 50 meshes with large bevel gear 47 and is provided at the inner end of a shaft 51, the outer end of which is rotatably secured to a connection 52.

The device operates as follows:

25 If it is desired to swing the propeller shaft and propellers to the right or left, this is done by the operator by pulling one or the other end of the cable to rotate pulley 37 in the desired direction rotating sleeve 30 to transmit a motion to swing by the intermediary of keys 29, link 16, and the universal joint, the propellers to the left or right.

30 If it is desired to lift or lower the propellers, this is done by the operation of bevel gear 50 turning screw bolt 43 to rise or to descent thus lifting by means of the claw the shaft 23 and by the intermediary of link 16 to raise or lower the propellers.

35 It will be understood that I have disclosed the preferred form of my invention only as one example of the many possible ways to practically construct my invention and that I may make such changes in the general arrangement and the construction of the minor details of my invention which come within 40 the scope of the appended claims without departure from the spirit of my invention and the principles involved.

45 Having thus described my invention, what I claim as new and desire to secure by Letters Patent is:

50 1. A boat propelling device comprising driving shafts, stub shafts carrying twin propellers, a universal joint coupling said driving shafts with the stub shafts, a rubber mantle covering the housing of the universal joint, a link connected with play to a sleeve carried by said stub shafts, a spindle movably connected to said link, keys on said spindle to guide the same in inner grooves of a rotatable sleeve, means for rotating said sleeve and spindle to displace the propellers laterally at an angle to the boat, and means connected with said spindle to raise and lower the propellers.

55 2. A boat propelling device comprising

driving shafts, and twin propeller bearing stub shafts, articulated to said driving shafts, a means for displacing said propellers laterally at an angle to the boat, connected to said stub shafts including a spindle having a head, a screw bolt having claws formed at its lower end to engage with play the head of said spindle, a bevel gear through which the threaded end of said bolt passes to be raised and lowered during the rotation of said bevel gear in one and the other direction, and means to rotate said bevel gear.

60 3. In a boat propelling device, driving shafts and stub shafts carrying twin propellers articulated to said driving shafts, a spindle passing through an opening in the bottom of the boat, means for connecting the lower end of said spindle with a certain play to said stub shafts, a housing in said boat, partitions dividing said housing into a plurality of superposed compartments, a sleeve provided with inner grooves, rotatably held in one of said partition walls through which said spindle extends, keys on said spindle guided in the grooves of said sleeve, a pulley 70 on said sleeve and a cable guided about said pulley intermediate its ends to control the rotation of said sleeve and spindle in one and the other direction to swing the propellers laterally at an angle to the boat for 75 steering the same.

75 4. In a boat propelling device driving shafts, and stub shafts carrying twin propellers articulated to said driving shafts, a spindle extending through the bottom of the boat, connections between said spindle and said stub shafts to swing the propellers laterally at a desired angle to the boat for steering the same, a head on said spindle, a screw bolt, claws formed with the lower end of said bolt engaging with play the head of said spindle, a large bevel gear through which said spindle extends having inner threads engaging the threads of said bolt, and a bevel gear in mesh with said large bevel gear, 80 means adapted to be operated from the operator to rotate said bevel gears to raise and lower said spindle and through the intermediary of its connections with the stub-shafts to raise and lower the propellers for 85 steering the same to the depth of the water in which the propellers revolve.

85 Signed at New York, in the county of New York and State of New York, this 26th day of January, A. D. 1932.

90 GISBERT RANKE.
